UNITED STATES PATENT OFFICE.

RICHARD L. VALENTINE, OF BROOKLYN, NEW YORK, ASSIGNOR TO JOHN W. VAN DYKE.

PORTABLE DERRICK.

SPECIFICATION forming part of Letters Patent No. 337,462, dated March 9, 1886.

Application filed February 28, 1885. Serial No. 157,429. (No model.)

To all whom it may concern:

Be it known that I, RICHARD L. VALENTINE, a citizen of the United States, and a resident of the city of Brooklyn, in the county 5 of Kings and State of New York, have invented a new and useful Improvement in Portable Derricks, of which the following is a specification; and I do hereby declare that the same has not, to my knowledge and belief, 10 been in public use or on sale in the United States for more than two years prior to this application.

My said improvement consists of the parts and various combinations of parts hereinafter 15 described and claimed.

The object of my said invention is to build a derrick which shall be simple in construction, be more easily moved and operated, and produce better results at a less cost, than any 20 derrick heretofore made for like uses and purposes.

My said invention and improvement has reference and application to the construction and operation of portable derricks for use in 25 the removal of earth, sand, clay, or stone from large or deep ditches or excavations, the building or rebuilding of sewers, the laying or re-laying of gas, water, oil, steam, or sewer pipe, the introduction to or removal from such 30 ditches, sewers, or excavations of the materials necessary to be used in the construction of such sewers, the loading or unloading of railroad-cars, vessels, lighters, or scows, and the filling of docks or cribs from vessels or scows. 35 I attain these objects by the mechanism illustrated in the accompanying drawings, in which—

Figure 1 is a perspective view of the entire derrick and its platform, the dotted lines there- 40 on showing a second mast and its attachments, which may be placed on any of the other three corners of the platform of the derrick. Figs. 2, 3, and 4 are views in elevation of the mast and gaff and the several constructions and 45 applications of the sheaves and other attach- ments thereto. Fig. 5 is a side view of one of the wheels upon which the derrick-platform runs when moved from place to place, and Fig. 6 is an end view of the same. Fig. 7 is a 50 side elevation of the sheave-holder or block permanently attached to the lower end of the gaff, as shown in Figs. 1 and 2. Fig. 8 is a

plan view of the same. Fig. 9 is a side view in elevation of a combined pivotal gaff-support and sheave holder or block, as shown in Fig. 4. 55

Similar letters indicate corresponding parts in the several figures.

Referring to the drawings, A is the platform of the derrick.

B is a hoisting machine placed in any de- 60 sired position on the derrick-platform A.

C is a stationary mast placed upon any one of the corners of the derrick-platform A, as shown in Fig. 1.

D is a slot in said mast C, to receive, and in 65 which is permanently secured, a sheave, E, and through which the hoisting-rope M passes. This sheave E may be placed below the gaff, as shown in Fig. 1, or above the gaff, as shown in Figs. 2, 3, and 4. 70

F F F are the braces which support the mast C on the derrick-platform A, as shown in Fig. 1.

G is the gaff.

H is the support to the outer end of the gaff G, the inner end of which support H is at- 75 tached to the top of the mast C by the eye I, and its outer end is attached to the outer end of the gaff G at J, as shown in Figs. 1, 2, 3, and 4.

K K K K are wheels upon which the der- 80 rick-platform runs.

L is a sheave suspended from the outer end of the gaff G, as shown in Figs. 1 and 3, or inserted in the gaff G, as shown in Figs. 2 and 4. 85

M is a hoisting-rope.

N N are bands around the mast C, by means of which and the pin O the gaff G is attached to the mast C, said pin O forming a pivot upon which the gaff G swings, as shown in Figs. 1 90 and 2.

P is an extended sheave-holder or block, which permanently attaches the sheave Q to the lower side of the gaff G, as shown in Fig. 1, or to the upper side of the gaff G, as shown 95 in Fig. 2.

Q is a sheave, which may be placed below the gaff G in the extended sheave-holder or block P, as shown in Fig. 1, or above the gaff G in the extended sheave-holder or block P, 100 as shown in Fig. 2, or inserted in a slot, S, in the lower end of the gaff G, as shown in Fig. 3, or in the combined pivotal gaff-support and sheave-holder or block R, as shown in Fig. 4.

R is a combined pivotal gaff-support and sheave-holder or block, which supports and holds the lower end of the gaff G and holds the sheave Q, and upon which support the gaff G swings. Said support is attached and secured to the derrick-platform A in front of the mast C, as shown in Fig. 4.

T is a pivotal support for the gaff G, upon which the gaff G swings, and which is attached and secured to the derrick-platform A in front of the mast C, as shown Fig. 3.

U is the tread of the wheels K K K when the same are used upon rails. V is the flange of said wheels. V becomes the tread of said 15 wheels when the same are not used upon rails. W in Fig. 8 is the pivot of the combined pivotal gaff-support and sheave-holder or block R. (Shown in Fig. 4.) X in Fig. 8 is the sheave-holder or block thereof, and Y 20 is the gaff-support thereof.

Z in Fig. 1 is a hook by which the weight or object is lifted, attached to the hoisting-rope M, as shown.

In operation the hoisting-rope M passes 25 from the hook Z, to which the weight or object to be lifted is attached, over the sheave L and under the gaff G, as shown in Figs. 1 and 3, or above the gaff G, as shown in Figs. 2 and 4, to the sheave Q, passing over the 30 sheave Q, as shown in Fig. 1, or under the sheave Q, as shown in Figs. 2, 3, and 4, from thence to and under the sheave E, as shown in Fig. 1, or to and over the sheave E, as shown in Figs. 2, 3, and 4, and thence through 35 the slot D in the mast C to the hoisting-machine B. (Shown in Fig. 1.)

In construction I prefer to use as wheels under the derrick-platform A such as are described and shown, but any suitable wheels 40 may be used. The outer end of the gaff G may be supported either as shown in Figs. 1, 2, 3, and 4, or by a block and fall from the eye I at the top of the mast C to the outer end of the gaff G at J, and fastened to the gaff G by 45 a cleat. The eye I, the sheaves E and Q, and the pin or pivot O, as shown in Figs. 1 and 2, or the eye I, the sheaves E and Q, and pivot T, as shown in Fig. 3, or the eye I, sheaves E and Q, and pivot W, as shown in Fig. 4, 50 must be so placed, respectively, that the hoisting-rope M, when between the sheaves E and Q, shall be in a straight line with the eye I and pin or pivot O, as in Figs. 1 and 2, or the eye I and pivot T, as in Fig. 3, or the eye I and pivot W, as in Fig. 4. By such a construction 55 the lower end of the gaff G will turn or swing on the pin or pivot O, as shown in Figs. 1 and 2, or on the pivot T, as shown in Fig. 3, or on the pivot W, as shown in Fig. 4. The support H will turn or swing in the eye I, and the hoisting-rope M, between the sheaves E and Q, will turn in the same direction without leaving the line with the eye I and the pivot at the lower end of the gaff G, all moving or turning as upon one center, hinge, or pivot. The gaff G will then swing easily, and

injury to the hoisting-rope M by its friction upon the sheaves E and Q will be prevented.

By having the sheave Q attached to the lower end of the gaff G by the extended block P, as 70 shown in Figs. 1 and 2, or having said sheave Q inserted in and fastened to the lower end of the gaff G, as shown in Fig. 3, or having said sheave Q attached to the lower end of the gaff G by the holder R, as shown in Fig. 4, and 75 having the hoisting-rope M pass from the sheave L over the sheave Q to the sheave E, as shown in Fig. 1, or under the sheave Q to the sheave E, as shown in Figs. 1 and 2, greatly relieves the lateral pressure of the lower end 80 of the gaff G against the mast C, and the pin or pivot O, as shown in Figs. 1 and 2, and the friction upon the pin or pivot O, and permits the gaff G to swing easily; or having the hoisting-rope M pass from the sheave L under the 85 sheave Q to the sheave E, as shown in Fig. 3 or Fig. 4, greatly relieves the lateral pressure of the lower end of the gaff G upon the pivot T, as shown in Fig. 3, or upon the pivot W, as shown in Fig. 4, thus lessening the friction 90 upon said pivots T or W and permitting the gaff G to swing easily.

The sheave E may be placed in any part of the mast C, either above or below the gaff G, as desired.

By placing another mast, C, on the corner of the derrick-platform, as shown by the dotted lines in Fig. 1, two gaffs may be used at one and the same time, and where the derrick-platform is run upon portable rails such rails may be taken up and removed from behind the derrick-platform and placed in front of the same by 95 means of said gaffs.

By placing the mast C on the corner of the derrick-platform A the same length of gaff 100 will reach a distance equal to one-half the width of the derrick-platform farther from the ditch or excavation where said derrick is being used than any portable derrick heretofore made will reach, and permits the gaff G to have 105 a much greater reach and swing, and permits of such gaff G being swung as well on the side as in front or in rear of the derrick-platform. It also enables the mast C to be secured to the derrick-platform at much less expense of construction than if the same is placed anywhere 110 else on the derrick-platform.

Having thus described my invention, what I claim as my invention, and desire to secure by Letters Patent, is—

1. In a portable derrick, the combination of a stationary mast, C, (having therein a slot, D,) an eye, I, and sheaves E and Q, with a pin or pivot, O, the said eye, pin, and sheaves being so placed, respectively, that a hoisting-rope, 125 M, between the sheaves E and Q is in a straight line with the eye I and pin or pivot O, as and for the purpose described and shown.

2. In a portable derrick, the combination of a stationary mast, C, (having therein a slot, D,) 130 an eye, I, and sheaves E and Q, with a pivot, T, the said eye, pivot, and sheaves being so

placed, respectively, that a hoisting-rope, M, between the sheaves E and Q is in a straight line with the eye I and pivot T, as and for the purpose described and shown.

5 3. In a portable derrick, the combination of a stationary mast, C, (having therein a slot, D,) an eye, I, and sheaves E and Q, with a pivot, W, the said eye, pivot, and sheaves being so placed, respectively, that a hoisting-rope, M, 10 between the sheaves E and Q is in a straight line with the eye I and pivot W, as and for the purpose described and shown.

4. In a portable derrick, an extended sheave-holder or block, P, attached permanently to 15 the lower end of a gaff, G, as and for the purpose described and shown.

5. In a portable derrick, the wheels K K K

K, having the tread U, and the flange V, as and for the purpose described and shown.

6. The combination, in a portable derrick, of 20 a sheave, E, permanently fixed in a slot in the mast, a sheave, Q, attached to or fixed in the lower end of the gaff, a sheave, L, inserted in or suspended from the outer end of the gaff, and the hoisting-rope M, as and for the pur- 25 poses described and shown.

7. In a portable derrick, a mast, C, permanently attached to the platform of the derrick at one of the corners thereof, as and for the purpose described and shown.

RICHARD L. VALENTINE.
